(57) **CLAIM**

The ornamental design for a bicycle stand, as shown and described.

DESCRIPTION

FIG. 1 is a rear view of a bicycle stand according to the present disclosure, with the base shown in environment. FIG. 2 is a right side view of the bicycle stand.

FIG. 3 is a front view of the bicycle stand.

FIG. 4 is a left side view of the bicycle stand.

FIG. 5 is a top view of the bicycle stand.

FIG. 6 is a bottom view of the bicycle stand.

FIG. 7 is a top-front-left perspective view of the bicycle stand, where the arm is in an extended configuration.

FIG. 8 is a top-front-left perspective view of the bicycle stand, where the arm is in a stowed configuration.

FIG. 9 is a bottom-left-rear perspective view of the bicycle stand with the base removed and the arm in the stowed configuration.

FIG. 10 is a cross-sectional view taken along line 10-10 in FIG. 5; and,

FIG. 11 is a cross-sectional view taken along line 11-11 in FIG. 5.

The dash-dash broken lines in FIGS. 1-11 illustrate portions of the bicycle stand and environmental subject matter that form no part of the claimed design.

The dash-dot-dash broken lines in FIG. 5 form no part of the claimed design.

The oblique solid line hatch shading in FIGS. 10-11 illustrates interior structure of the bicycle stand.

The oblique broken line hatch shading in FIGS. 10-11 illustrates interior structure that forms no part of the claimed design.

1 Claim, 11 Drawing Sheets
